UNITED STATES PATENT OFFICE

WILLIAM A. STELLING, OF PROVIDENCE, RHODE ISLAND, ASSIGNOR TO THE TEXTILE-FINISHING MACHINERY COMPANY, A CORPORATION OF RHODE ISLAND

TENTER CLIP

Application filed September 8, 1930. Serial No. 480,409.

This invention relates to a tenter chain link for engaging and directing a web in its desired travel through a machine; and has for its object to provide a plate for the fixed jaw 5 of the link which may be readily removed therefrom.

A further object of the invention is to provide means for holding a plate on the fixed jaw without the use of rivets, whereby when 10 the same is resurfaced by grinding, it may still be retained as securely on the jaw as when first positioned thereon.

A still further object of the invention is to provide a removable plate for the fixed jaw 15 which is frictionally held in position by providing slots in or about the fixed jaw for frictionally receiving portions of the plate.

A still further object of the invention is the provision of a construction in which the 20 plate may be slid into position by forcing the same along the surface of the fixed jaw in an arbor press or the like, and which may be removed by being forced in the opposite direction, the same being retained by frictional engagement in working position.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a perspective view of the back of 35 the tenter chain link showing my plate and improved mounting therefor in the fixed jaw;

Fig. 2 is a perspective view of the plate alone;

Fig. 3 is a face view of the link with the 40 gate or movable jaw removed showing the plate as positioned thereon;

Fig. 4 is a view similar to Figure 3 with the plate removed and showing the slots at the juncture of the overhanging portion and the 45 fixed jaw, and also the slots in the edges of the fixed jaw extending inwardly from the face thereof;

Fig. 5 is a section on line 5—5 of Fig. 3;

Fig. 6 is an enlarged fragmental detail 50 showing a portion of the stock of the over-

hanging portion as forced into an opening in the plate for additionally securing the same in working position.

It is found in practice that a certain amount of chattering or vibration of the movable jaw 55 occurs in tenter links, especially during the return or inoperative travel of the chain, and that this chattering causes the wearing of a groove in the fixed jaw, which groove is usually removed by grinding to resurface the 60 fixed jaw, bringing the surrounding area of the jaw to the depth of the groove.

Plates of a material harder than the body link are used for covering this fixed jaw, which plates are often riveted in place, and 65 when the groove is worn in the plate and the same resurfaced by grinding, the heads of the rivets become thinner and correspondingly weakened, and the plate is not as securely held in position; and in order to avoid this 70 riveting and weakening of the rivets, and to provide a construction which is extremely simple in assembly and operation, I have recessed portions of the jaw and so formed the plate that it will enter these recesses, the sizes 75 of the plate and recesses being such that a forced fit is required, the friction of the walls of the recesses holding the plate in working position; also additional holding means may be provided where desired to assist the frictional holding of the plate in position; and the following is a detailed description of the 80 present embodiment of this invention illustrating the preferred means by which these advantageous results may be accomplished. 85

With reference to the drawings, 10 designates the body portion of the tenter link having a fixed jaw portion 11 and overhanging portion 12, upon which overhanging portion there is hingedly mounted the gate or movable jaw 13 with its opening arm 14 projecting upwardly therefrom. An ear 15 extends from one side of the link to project between a pair of ears 16 and 17 of another link at the other side thereof, the adjacent links 95 receiving pivot pins in the openings 18 to connect the links in the chain.

A work engaging plate 19 covers the working surface of the fixed jaw 11 and with which the movable jaw 13 engages in the ab- 100

sence of the work or web as on the return or inoperative movement of the chain. This engagement is often in the nature of chattering on the plate 19 which in time forms a 5 groove therein which must be removed by resurfacing. A recess 20 is formed at the juncture of the overhanging portion 12 with the fixed jaw portion 11 as illustrated in Figures 4 and 5, the same being provided between the brace 21 for the overhanging member and the fixed jaw and is of a size to receive and frictionally hold the plate 19 therein. The sides of the fixed jaw are also received as at 22 inwardly from the sides thereof 10 and extending forwardly to the face 23 of the fixed jaw for receiving the inturned portions 24 of the fingers 25, or the reversely bent portions of the plate to frictionally hold the same therein. The fit between the walls 20 of the recesses 20 and 22 and the portions 24 and 26 of the plate are such as to require the plate being forced into position by an arbor press by sliding the plate inwardly from the face of the fixed jaw until its edge is flush 25 with the face 23 thereof.

Openings 27 are provided in the plate in such a position as to be partially covered by the wall 28 of the recess 20, whereby a prick punch or other upsetting tool may be used 30 to force the stock 29 of the wall 28 into the opening 27 to additionally secure the plate in position. The amount of stock 29 which is forced into this opening, however, does not require cutting off before removing the plate 35 from position and mounting a different plate on the jaw, as pressure at the point 30 of the plate on either side of the overhanging portion 12 will force the plate from its frictional engagement with the walls of said recesses and at the same time move from its path the portion 29 of the stock upset into the opening.

By this construction, a plate is formed which is secured in position without the use 45 of rivets. When worn, by engagement with the gate or movable jaw its surface may be ground down to remove the groove without weakening the holding means, and when desired to be removed for remounting a fresh 50 plate, the same may be slid from position by suitable pressure and a new plate forced by sufficient pressure into position, all without removing the upset ends of rivets or other more laborious operations.

While I have described certain construction forms which embody the principles of my invention, it is obvious that other desired changes in arrangement may be made within the spirit and the scope of the invention as defined in the appended claims.

I claim:

1. A tenter chain link comprising a body with recesses therein and having a portion providing a fixed jaw, a hingedly mounted gate thereon providing a movable jaw, and a

plate having an opening therein on said fixed jaw frictionally received in said recesses and a portion of said body extending into said opening for holding said plate in position.

2. A tenter chain link comprising a body having a portion providing a fixed jaw having recesses therein, a hingedly mounted gate thereon providing a movable jaw and a plate positioned in said recesses and having an opening therein, said opening being positioned to extend beneath the portion forming the wall of said recess and said portion being upset to extend into said opening.

3. A tenter chain link comprising a body having a portion providing a fixed jaw having recesses therein, a hingedly mounted gate thereon providing a movable jaw, a plate in said recesses, said plate having an opening therein inwardly from the periphery thereof, a portion of said body extending over and into said opening to assist in securing the plate in position.

4. A tenter chain link comprising a body having a portion providing a fixed jaw with a portion overhanging the same, a movable jaw hinged to said overhanging portion, a plate forming the contact surface of said fixed jaw, said overhanging portion having a recess at its junction with said fixed jaw, the bottom wall of said recess being a continuation of the top surface of said fixed jaw, and in the same plane therewith, said plate extending into said recess and frictionally engaging the walls thereof to hold the plate in position on said fixed jaw.

5. A tenter chain link comprising a body having a portion providing a fixed jaw with recesses from its opposite sides extending inwardly from the face thereof and with a portion overhanging the same, a movable jaw hinged to said overhanging portion, a plate forming the contact surface of said fixed jaw, said overhanging portion having a recess at its junction with said fixed jaw, said plate extending into said recesses and frictionally engaging the walls thereof to hold the plate in position on said fixed jaw.

6. A tenter chain link comprising a body having a portion providing a fixed jaw with recesses from its opposite sides extending inwardly from the face thereof and with a portion overhanging the same, a movable jaw hinged to said overhanging portion, a plate forming the contact surface for said fixed jaw, and having an opening therein, said overhanging portion having a recess at its junction with said fixed jaw, said plate extending into said recesses and frictionally engaging the walls thereof, and a portion of one of said walls being extended into said opening to hold the plate in position on said fixed jaw.

7. A tenter chain link comprising a body having a portion providing a fixed jaw with front and side walls, said side walls having

recesses from its opposite sides inwardly from the front wall thereof and with a portion overhanging the fixed jaw, a movable jaw hinged to said overhanging portion, a 5 plate forming the contact surface of said fixed jaw and provided with fingers to extends along the sides of said body and entering the recesses therein from the front wall of the jaw.

10 8. A tenter chain link comprising a body having a portion providing a fixed jaw with front and side walls, said side walls having recesses from its opposite sides inwardly from the front wall thereof and with a portion overhanging the fixed jaw, a movable 15 jaw hinged to said overhanging portion, a plate forming the contact surface of said fixed jaw provided with reversely bent portions to extend along the sides of said body 20 and into said recesses from the front wall of the jaw.

9. A tenter chain link comprising a body having a portion providing a fixed jaw with front and side walls, said side walls having 25 recesses from its opposite sides inwardly from the front wall thereof and with a portion overhanging the fixed jaw, a movable jaw hinged to said overhanging portion, a plate forming the contact surface of said 30 fixed jaw provided with reversely bent portions to extend along the sides of said body and into said recesses, said plate being slideable into position with the portions entering said recesses from the front wall of the jaw.

35 In testimony whereof I affix my signature.

WILLIAM A. STELLING.
